[57] CLAIM

The ornamental design for a illuminated disc flyer, as shown and described.

DESCRIPTION

FIG. 1 is a perspective view of an illuminated disc flyer showing my new design;

FIG. 2 is a top view thereof;

FIG. 3 is a bottom view thereof;

FIG. 4 is a front elevational view thereof;

FIG. 5 is a rear view thereof; and,

FIG. 6 is a left side elevational view with the right side being a mirror image rear view thereof.

The broken line showing of a battery, a battery holder, and electrical connections in FIG. 3 is for illustrative purposes only and forms no part of the claimed design.
